UNITED STATES PATENT OFFICE.

HERBERT J. SKIPP, OF NEWARK, NEW JERSEY.

BUTTON-FORMING MACHINE.

Application filed October 29, 1921. Serial No. 511,399.

To all whom it may concern:

Be it known that I, HERBERT J. SKIPP, a citizen of the United States, and a resident of Newark, county of Essex and State of New Jersey, have invented certain new and useful Improvements in Button-Forming Machines, of which the following is a specification.

This invention relates to an improved button forming machine in which a piece of material, such as the so-called vegetable ivory, is held in a clamp while a tool is revolved on the face of the material to form the face and the rim of the button.

The invention relates to a machine of this kind in which the holding of the piece of material is firm, even though the material which is cut into slices or small slabs is rough and uneven on its edges, since the holding means is automatically adjusted to such uneven surface when it is forced into holding position.

The invention relates also to a cutting means which first cuts the blank to approximately the form of the button and then cuts the blank so as to finish the surface thereof, these cutters being preferably operated into cutting position by a single means. The cutters are easily removed or replaced in case of chipping or breakage.

The invention is illustrated in the accompanying drawings, in which Figure 1 is a side view of a button forming machine broken away at portions thereof, this machine illustrating one form of my improved invention. Figure 2 is a central vertical section of a cutter used in the machine. Figure 3 is a section on line 3—3 in Figure 2. Figure 4 is a sectional view showing a front and rear cutter and illustrating a part of the clamp for holding a piece of material from which the button is made in position. Figure 5 is a perspective view of one portion of the cutter, and Figure 6 is a perspective view of another portion of the cutter. Figure 7 is partly an elevation and partly an end view and shows an improved clamp used for holding the material from which the button is made in position, and Figure 8 is a side view of the construction shown in Figure 7.

The machine comprises a suitable support or bed plate 10 having legs 11 which support it at the proper working height, and at a suitable point, usually substantially centrally located on the table 10, is a fixed

member 12, against the face of which the piece of material 13 from which the button is to be made is held. The button material is formed, previous to insertion in the machine, in the form of thin slabs or flakes, and when the material is what is known as vegetable ivory it is cut from irregular shaped blocks, and the pieces that are cut therefrom, while they are flat for the major portion of their faces, are uneven at their edges and not at all symmetrical.

When held by a substantially rigid clamp the uneven contour of the material does not permit, in many cases, of a secure clamping of the piece of material, and when the cutters are put in operation, these cutters operating rotatively on the face of the material to cut or scrape from the material the button, the piece moves slightly and chatters or vibrates, which not only provides for an uneven product, but results in the early breaking of the cutter.

The present clamp is one in which the piece of material is tightly held, since it comprises fingers which can be selectively forced into clamping position so that the one that clamps the material first interferes in no way with the forward movement of the other clamping fingers until they are all in firm engagement with the material to be held.

One form of clamp is shown in the drawings, comprising end plates 14, in which are slidably arranged the bars 15, these bars being preferably arranged in pairs on opposite sides so as to leave a sufficient clearance for the operation of a cutter to be hereinafter described, which cutter operates through this clamping device, the bars 15 being provided with suitable fingers 16 which project inwardly, but not far enough to interfere with the operation of the cutters, being adjusted to terminate short of the diameter of the cutting device and being normally held back by suitable springs 17.

Each pair of bars 15 has its members connected by an arm 18, these arms being arranged so that they can rock in the bars and are preferably passed through the bars, this rocking being permitted by rounding the walls of the perforation 19 through which these bars project, the bars being held in position by suitable means, such as the screw 20 above one of the bars 15 of a pair and having a head 21 on each arm in the other bar of such pair.

The arms are engaged by pins 22 of a yoke 23 so that the arms of the yoke extend up on either side and have their pins engaging the arms that connect the bars so that the bars can be pushed against the influence of the springs 17, which springs normally hold the bars yieldingly against movement in their normal or retreated position. The yoke 23 is swivelled so that it can be 10 swung to compensate for uneven movement of the bars, the arms in turn rocking to compensate for uneven movement of the bars.

Suitable means for operating the yoke is installed, the form shown comprising the 15 short shaft or stud 24 to which the yoke is swivelled, as by means of the bolt 25, the stud 24 fitting into the socket 26 at the end of the lever 27, the lever being pivoted, as at 28, and being suitably connected to a 20 treadle or foot piece 29 which engages the extension 30 of the lever 27 by means of the pin 31.

It will be evident that when a piece of material 13 is placed against the face 32 of 25 the fixed member 12 and the swivelled yoke is pushed forward, it pushes on the arms 18, these arms pushing the bars 15 forward and causing the fingers 16 to engage the material. This material being uneven, the bars will 30 compensate therefor since the stopping of any of the bars acts as a fulcrum for the further movement of the arm that connects the bars in that pair, or as a fulcrum for the swinging of the swivelled yoke, and the 35 fingers are all pushed up to tight clamping position on the uneven surface of the material.

When the pressure is released, after the work is completed, the springs 17 pull the 40 bars back, and these, through the arms and the yoke, return all the portions of the clamp to their normal inoperative position.

The button may be cut from the blank from one side and then the blank reversed 45 and a cutter operated against the other side, but I prefer to use two cutters, one on the back and one on the front of the button, one of the cutters operating through a perforation 33 in the fixed member 12 and the other 50 cutter operating through the clamping device hereinbefore described. These cutters, except for their contour, can be alike, and I will describe the construction of one, which will be understood as being applicable to 55 the other.

Bearings 34 and 35 on the bed plate 10 slidably support the sleeve 36, within which is slidably arranged the shaft 37, the sleeve 36 being operated by a belt 38 passing over 60 a pulley 39. The sleeve and the shaft are adapted to operate rotatably together, but the shaft 37 is slideable longitudinally in the sleeve 36. The sleeve 36 is provided with one cutter or blade thereof, as at 40, being 65 adapted to be secured in place by a suitable

screw 41, the rear end of the cutter 40 having the part 42 which rests against the flattened side 43 of the shaft 37. This cutter is held against movement longitudinally, except with the sleeve, and will be identified by 70 being called the movable cutter, and it is usually arranged radially in the sleeve so that its cutting edge rotates circumferentially relative to the axis of the shaft.

The fixed cutter 44 permits the movement 75 of the movable cutter by reason of the slot 45 through which the screw 41 projects, the cutter being secured at its rear end, by means of a screw 46, to the shaft 37, and, being clamped tightly by the screw 46, moves with 80 the shaft 37 when the shaft 37 is moved longitudinally in the sleeve 36. The edges of the cutters are made with a contour which defines the face and rim of the button, and being arranged face to face, as will be seen 85 in Figure 2, their line of cutting relative to the axis is the same, and they are also arranged so that the path of travel of one is coincident to the path of travel of the other on the piece of material to be cut, so that 90 one, such as the fixed cutter 44, is used for "roughing" and taking out the rough part of the material, and the movable cutter 40 is used for the finishing to give the button its smooth surface.

It will be evident that in any breakage of the cutter it is easily replaced and the expense of making a new cutter is cut down, since only one-half of the cutter at any time is liable to damage.

At 47 I show a cutter similar to the one just described, except that here the contour of the cutting edge 48 of the cutter is different so as to give the proper contour to the back of the button, as will be evident 105 from Figure 4.

When the front and rear of the button are cut with the same machine I prefer to use a single means for first advancing one set of cutters which cut the front face of 110 the button, and then retreating this set of cutters and at the same time advancing the other set of cutters 47 to cut the rear face of the button. One form of accomplishing this is illustrated in Figure 1, in which the slide 49 is suitably operated, as by means of a link 50 connected to a lever 51 which forms a handle with a hand feed 52 thereon and a suitable weight 53 to keep the parts balanced and to provide for an easier operation.

Since both ends are operated similarly I will describe but one end of the machine, which comprises a block 54 fastened to the sleeve 36, this block 54 being on the slide 49 115 and having on its top edge a bearing 55 through which the shaft 37 slides. The shaft 37 is provided with a plate 56 which is preferably adjustable, as by reason of the nuts 57 on the screw-threaded end 58 of the shaft 120 125 130

37, and is provided with a stem 59, the front end of which engages the end 60 of the bed plate of the machine. The stem 59 is slidably arranged in the block 54, and a guiding finger 61 is also slidably arranged in the block 54 and is a guiding finger to keep the parts better aligned. A spring 62 yieldingly and normally holds the block 54 pushed back to its normal position, which in turn holds the sleeve 36 back and thus keeps the finishing cutter 40 in rear of the roughing cutter 44.

Assuming that the handle 52 is swung upward, the slide 49 is moved to the left in Figure 1 and the shaft and the sleeve are both moved forward together to bring the roughing cutter in contact with the piece of material 13. The end of the stem 59 is stopped when it engages the part of the machine against which it is projected, the plate 56 is stopped, and consequently the shaft 37 is stopped, and the roughing cutter rotates in position, it having been cutting during part of this forward movement, the finishing cutter being held in rear of the cutting edge of the roughing cutter; in other words, it has maintained its normal position.

On a further movement, however, of the handle 52, the slide 49 pulls the block 54 against the influence of the spring 62, this lost motion device permitting such further movement of the sleeve 36, and while the shaft 37 and its cutter are held stationary, the sleeve 36 is advanced and it projects the finishing cutter 40 so that its cutting edge slowly passes beyond the roughing cutter and continues the cutting operation, this being continued until the proper finish is secured or until the button is entirely cut from the blank, this usually being the case since the cutters are normally provided with the edge 63, which, as will be seen from Figures 4 and 6, cuts through to meet the cut made by the cutter 47 and the button is cut from the blank at the edge of the button.

When this has been accomplished the handle 52 is again lowered and all the parts are then retreated into the position shown in Figure 1. While this cutting has been going on, the clamp, which has been previously described, has been holding the material 13 solidly in position, and after the cutting is completed the foot pedal is released to permit the clamp to be returned to its normal position through the influence of the springs 17, and the machine is ready for the insertion of another piece of material.

This method of cutting the button is expeditious and economical and is easy of operation.

It will be also evident that the roughing tool, when it first engages the material, or if, at any stage in the roughing, there is an uneven surface encountered or hard.

gritty places in the material, becomes 65
chipped, which forms an uneven cutting
edge and results in concentric or circular
ridges. In the old style tool this would re-
quire the making of a new cutter, but in the
present tool any slight unevenness in the 70
roughing cutter is not a serious defect be-
cause the finishing cutter, when it is ad-
vanced, removes the slight imperfections
from the face of the button. In other words,
a perfectly smooth finish is possible on the 75
face of the button, which is almost impos-
sible when the buttons are finished with one
solid tool.

It will be understood that minor changes can be made in the proportions and arrangement of the parts without departing from the scope of the invention. 80

I claim:

1. A button forming machine comprising a fixed member, a frame opposite the fixed member, inwardly projecting fingers supported so as to slide on the frame, and a single means for selectively pressing the fingers in holding contact with the fixed member. 85

2. A button forming machine comprising a clamping device, said device comprising a frame, pairs of rods slideable in the frame, an arm connecting each pair and adapted to rock in said rods, and a swivelled element 955 rockingly engaging the arms to move the arms and fingers forward.

3. A button forming machine comprising a clamping device, said device comprising a frame, pairs of rods slideable in the frame, an arm connecting each pair and adapted to rock in said rods, and a swivelled yoke movable to rockingly engage the arms and move them forward. 100

4. A button forming machine comprising 105
a clamping device, said device comprising a
frame, pairs of rods slideable in the frame,
an arm connecting each pair and adapted
to rock in said rods, a swivelled yoke move-
able to rockingly engage the arms and move 110
them forward, and springs connected to said
rods to yieldingly hold them in normal po-
sition.

5. A button forming machine comprising a frame having opposed standards at its ends, rods sliding in the standards, arms connected to selected rods and in rocking engagement therewith, inwardly projecting fingers on said rods, springs to yieldingly hold the rods back, a swinging lever, and a yoke swivelled on the lever, said yoke having on its arms means to rockingly engage the arms of the rods to move the rods against the influence of the springs. 115 120

In testimony that I claim the foregoing, I 125
have hereto set my hand, this 28th day of
October, 1921.

HERBERT J. SKIPP
